EDUCATIONAL DISPLAY DEVICE

Howard Meuche, R.R. 1, Fort Branch, Ind.

Filed Aug. 8, 1961, Ser. No. 66,245

Term of patent 14 years

(Cl. D25—1)

FIG. 1

FIG. 2

FIG 3

FIG. 1 is a front top perspective view of an educational display device embodying my design; and

FIG. 2 is a rear bottom perspective of said educational display device; and

FIG. 3 is a plan view of a blank from which the display device is formed, all printed matter being omitted from the said blank.

The dominant features of my design reside in the portions shown in full lines and are characterized by depressed ends sloping continuously from one side of the display device towards the other side and intersected by a vertical partition.

I claim:

I claim:
The ornamental design for an educational display device, substantially as shown and described.
